UNITED STATES PATENT OFFICE.

ROBERT HEAD, OF YONKERS, NEW YORK, ASSIGNOR TO THE AEOLIAN COMPANY, A CORPORATION OF CONNECTICUT.

APPARATUS FOR MAKING PHONOGRAPH RECORDS.

1,419,851.

Specification of Letters Patent. Patented June 13, 1922.

Original application Serial No. 14,404, filed March 15, 1915. Divided and this application filed April 11, 1919. Serial No. 289,372.

To all whom it may concern:

Be it known that I, ROBERT HEAD, a citizen of the United States of America, residing at Yonkers, in the county of Westchester, State of New York, have invented certain new and useful Improvements in Apparatus for Making Phonograph Records, of which the following is a specification.

The present invention relates to apparatus for making phonograph records and more especially to those of the flat or disk type having lateral or zig-zag sound grooves. The primary object of the invention is to provide a novel and improved apparatus of this character whereby a copy either in the form of the commercial record or a die adapted to be used in the making of the commercial records may be made in such a manner that the sound waves of the original record will be accurately reproduced in the copy but imperfections in the original will be practically eliminated from the copy, the copy possessing other advantages over those made in the usual manner, as will hereinafter appear.

To these and other ends the invention consists in certain improvements and combinations and arrangements of parts, all as will be hereinafter more fully described, the features of novelty being pointed out particularly in the claims at the end of the specification.

In the drawing, which illustrates the preferred embodiment of the invention:

Figure 1 is a top plan view of an apparatus constructed in accordance with the present invention;

Figure 2 is a view, partly in section and partly in elevation, of the apparatus as shown in Figure 1;

Figure 3 is a diagrammatic view on an enlarged scale illustrating the manner in which the tracer cooperates with the original record from which the copy is to be made;

Figure 4 is a fragmentary view showing the appearance of the sound grooves in the original; and

Figure 5 is a fragmentary view showing the appearance of the sound grooves produced in the copy.

Similar parts are represented by the same reference characters in the several views.

The present invention provides an apparatus which is capable of use generally where

it is desirable or necessary to produce photographic copies from originals which are rough or otherwise contain imperfections which should be practically eliminated from the copies. The apparatus is especially adapted for use in the production of phonograph records of the disk type having lateral or zig-zag sound waves, by a method such as that described in my application Serial No. 14,404, filed March 15, 1915, of which application the present is a division.

The preferred embodiment of the invention is shown in the accompanying drawing and will be hereinafter described in detail. It is to be understood, however, that the invention is not restricted to the precise construction as equivalent constructions are contemplated and will be included within the scope of the claims.

In the present instance, the apparatus comprises a suitable base 1 which supports a pair of turn tables 2 and 3. These turn tables are mounted on parallel axes or spindles 4 and 5 and they are revolved in synchronism or at the same speed by any suitable mechanism which operates a shaft 6 which is connected to the turn tables by the spiral gearing 7 and 8. The original 9 from which the copy is to be made is fixed on the turn table 3 while the blank or plain disk 10 which subsequently becomes the copy is fixed on the turn table 2. In the present instance, the copy will be one-half the size of the original, this reduction presenting the advantage that imperfections in the original will be reduced correspondingly with the reduction in the size of the copy.

An arm 11 which is of rigid construction is supported by the bearing 12 to swing in a plane parallel to the plane of the original and the copy. This arm extends through a slot 13 formed in a stationary guide member 14, the upper wall 15 of the slot being parallel to the plane of the original and the copy. The guide member is preferably curved or concentric with the axis of the bearing 12, as shown. A spring 16 on the under side of the bar 11 bears on the lower wall 17 of the slot and this spring acts to yieldingly press and hold the top of the arm 11 against the top wall 15 of the slot, thus insuring movement of the arm 11 in a true plane. A tracer 18 is carried by the arm 11 toward its free end. The point or

operative end of the tracer is rounded as shown in Figure 3 and the tracer is yieldingly supported in the arm 11 so that it may move in a direction transverse to the 5 plane in which the arm swings. As shown, the tracer is slideable freely in a bore 19 in the arm, the tracer having a reduced portion of stem 20 which is slideable in a cap 21 threaded in the bore 19, and a compression spring 22 is coiled about the stem 20 10 and bears at its ends on the tracer and the cap respectively. As a result, the rounded point of the tracer is always pressed yieldingly into operative relation with the sound groove 23 or other line to be followed on the original. Where the original 15 from which the copy is to be made comprises an etched record produced in accordance with the method described in my 20 application hereinbefore referred to, the rounded point or end of the tracer will be maintained yieldingly in contact with the edges of the sound grooves notwithstanding irregularities and variations in the width or 25 shape of the groove resulting from the etching operation. This yielding pressure upon the tracer will not only maintain the tracer in cooperative relation with the grooves so that it will follow the groove, but 30 it will also center the tracer between the two walls or edges of the groove even though the groove may vary in width or shape or have other irregularities, in consequence of which the axis of the tracer will 35 follow the median line of the groove and it will reproduce in the copy a groove which conforms with the median line of the groove in the original and, hence, the irregularities of the original will be substantially corrected or eliminated in the copy. The copy 40 is made on the blank 10 by a tracer cutting or other type of record forming tool 24. A cutting tool is shown in the present instance it being preferably so shaped that it 45 will produce a distinctively V-shaped groove 50 in the copy. A groove of this form will keep the reproducing stylus well down in the groove with the advantage that the reproduction of sound is more accurate and it 55 is of greater volume. In view of the fact that the tool 24 is mechanically guided instead of acoustically driven as in the usual recording method in which the cutting tool is attached to the recording diaphragm, a much deeper sound groove can be produced than has heretofore been found practicable. Furthermore, the mechanical guiding of the copying tool enables records to 60 be made not only in wax-like materials but such records can be made in any appropriate metal such, for example, as steel, and the like. If the record is made in steel, it may be subsequently hardened and used as a dye. A thin sheet of soft steel or 65 nickel or other appropriate metal may be

pressed into the face of the die so that it takes an impression of its groove and the sheet so made may then be backed up, hardened and used as a matrix to press the commercial records. Also, an electro-type 70 capable of being stripped, can be made from the copy, the electro-type being then backed up in the usual way and used as a matrix to press the commercial records.

I claim as my invention:—

1. In combination, means for rotatably supporting a zig-zag grooved sound record and a record blank, a tracer having a rounded end wider than the groove of the sound record, a record-forming tool, and means 80 operatively connecting the tracer and tool, said tool forming a record on said blank as the tracer follows said groove, the tracer being movable relatively to the tool whereby the tracer is yieldingly pressed into the groove so as to contact with both sides thereof and to compensate for variations in the distance between the portions of the sound record engaged by the tracer and the plane in which the tool operates.

2. In combination, a pivoted pantograph arm, a tracer located toward the free end of said arm, means for rotatably supporting a zig-zag sound record to be followed by said tracer, a record-forming tool on said arm between its pivot and said tracer, and means for rotatably supporting a record-blank to be operated on by the record-forming tool.

3. In combination, a pivoted pantograph 100 arm, a tracer located toward the free end of said arm, means for rotatably supporting an enlarged zig-zag sound record to be followed by said tracer, a record forming tool on said arm between its pivot and said tracer, and means for rotatably supporting a record blank to be operated on by the record-forming tool, the axis of said rotatable supporting means and the pivot of the pantograph arm being in substantial 110 alignment.

4. The combination of a support for a zig-zag grooved sound record, a support for a record-blank, means for moving said supports concurrently, a pantograph arm 115 mounted to swing across the record and record-blank, a tool connected to said arm and operative on the record-blank, and a tracer connected to said arm and having a rounded portion which is wider than and is adapted 120 to cooperate with the groove in the record.

5. The combination of rotatable supports for a zig-zag sound record and record-blank respectively, means for revolving said supports synchronously, a pantograph arm 125 mounted to swing in a plane parallel to the record and record blank, a tool connected to said arm and operative on the record-blank, and a tracer connected to said arm having a rounded end wider than and co- 130

operative with the edges of the groove in the record, said tracer being yieldable relatively to said arm in a direction transversely of the plane in which said arm swings to compensate for variations in the width of the groove in the sound record.

6. The combination of rotatable supports for a zig-zag sound record and a record-blank respectively, means for revolving said 10 supports synchronously, a pantograph arm

pivoted to swing across said supports and connected to a tracer which cooperates with the sound record and a tool which cooperates with said blank, a guide, and means for holding said arm in engagement with said 15 guide whereby the arm is caused to swing in a true plane.

In testimony whereof I have hereunto set my hand.

ROBERT HEAD.
